WILLIAM F. RAMONT, OF GLENDALE, CALIFORNIA

TIE AND COLLAR STAY

Application filed August 1, 1931. Serial No. 554,424.

This invention relates to articles for use with the soft collars either of the attached or detached type such as are now commonly worn by men, to aid in keeping the front of the collar in a neat appearing condition.

The principal object of my invention is to provide a device for the purpose which besides maintaining the front of the collar or its flaps in the neat appearing condition from top to bottom will hold the tie, either of the bow or four-in-hand type, in snug fitting relation to the collar when once properly tied, and will prevent the tie from subsequently dropping. The device is also constructed or shaped so that the natural and desired contour of the front edges of the collar flaps is maintained and an unduly stiff appearance is avoided. The device is also arranged so as to give according to the flare or angle of separation of the collar flaps, which angle differs with different styles of collar.

The device is also arranged so that it may be easily mounted in place or removed from the collar without damage to same, and which does not need to be removed every time the shirt or collar are taken off. Also the device is completely invisible when the collar and tie are assembled in their proper relationship, so that nothing is exposed to give evidence of the presence of the stays.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a front fragmentary outline of a collar and tie assembly showing one form of the stay in place.

Fig. 2 is a similar fragmentary view with

one flap of the collar turned to show the mounting of one of the stay elements therein.

Fig. 3 is a perspective view of the complete stay detached.

Fig. 4 is a similar view of another form of stay.

Fig. 5 is a view similar to Fig. 2 showing the mounting of the latter form of stay.

The stays are made of wire of a resilient and readily yieldable nature, and referring for the time being to the type shown in Figs. 1 to 3, each stay element comprises a relatively straight member 1 somewhat shorter than the flap 2 of the collar at its end. At its lower end the member 1 is provided with a small knob 3 or the like so as to provide a rounded or blunt end which is not likely to pierce the fabric of the collar and project to the exterior. At its upper end said member is formed with a sharp U-bend 4 which forms a resilient connection with a relatively short arm 5. This arm extends down alongside the member 1 in normally parallel relation thereto, and has a length substantially equal to the width of the tie bar B. At its lower end the arm 5 is bent at a right angle to form a horizontally extending bar 6. The bar on one stay element is formed on its outer end with a hook 7 while the bar on the other element is formed with an eye 8 for detachable engagement with the hook.

When mounting the stay in the collar a hole 10 is punched by means of a suitable tool through one thickness of the outer and lining fabric of the collar at the back or inside near the top and adjacent the edge of the flap, so as to communicate with the space formed between the usual double seams. The position of this hole is clearly indicated in Fig. 2. The knob 3 is then inserted through the hole and the stay member 1 is pressed down so that it is sheathed for its full length inside the collar, until the bend 4 is adjacent the hole 10. Stays suitable for collars having different lengths of flap should

be used, so that when the stay is thus positioned the nob 3 is some little distance short of the point of the collar. The arm 5 then remains outside the collar but, once at the back or under the flap it is not visible when the collar is properly associated with the shirt.

When both stay elements are in place the collar and tie are put on in the usual manner and the hook and eye of the bars are engaged under the bow or knot of the tie. The bars 6 then extend from in front of to behind the plane of the tie band which extends around the collar and then form supports for said band adjacent its junction with the bow or knot. Said band is then prevented from dropping down and the knot or bow are thus held in their proper position between the flaps and relative to the top of the collar. The wire of which the elements is made being resilient and readily yieldable, the angle between the members 1 when assembled in the collar may differ according to the flare of different collar models, without having to alter the angle of the bars 6. Adjacent the top and bottom the members 1 are formed with slight inward and outward bends respectively as shown at 11, which allow the edges of the flaps to have a certain non-straight or broken contour and avoid giving the collar too stiff an appearance.

In the form of stay shown in Figs. 4 and 5 the same results are obtained but the construction is somewhat different. In this form the members 12 and 13, which are the equivalent of the parts 1 and 5 in the first type, are connected at the bottom of the stay and the members 13 extend nearly to the top of the members 12. Said members 13 at their upper ends are bent sharply over as at 14 and then extend down a short distance as at 15; the hook and eye arms 6a being formed on and projecting from the lower ends of the portions 15.

In mounting this type of stay on the collar the hole 10a in each flap is placed in such position that when the bend 14 of the stay element is adjacent the hold, the lower ends of the members 12 and 13 are near the tip or point of the collar flap as shown in Fig. 5. The members 12 and 13 are both sheaved in the collar for practically their entire length, only that portion of the member 12 above the bend 14 being exposed to the back surface of the collar. In this type of the stay, the bend at the lower end of the members 12 and 13 provides the desired rounded end and takes the place of the knob 3 shown and described in the first type. To prevent the projecting and exposed end of the member 12 from possibly protruding through the fabric, the wire is preferably formed with a scroll arranged to rest flatly against the back surface of the collar adjacent the top.

The scroll 16 is, as shown, bent slightly

backward to fit and conform to the slight backward tilt of the collar and thus make a more proper rest and support for holding the collar in a natural position.

The inverted U-construction 14-15 provides resiliency and allows the stay to conform to any angle or taper of the collar. Furthermore, bending backward, as it does, away from the necktie, it forms a socket wherein the knot of the tie rests snugly and is held in place until released by the unhooking of the stays.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A stay for soft collars comprising separate stay elements, each element including a relatively stiff member adapted to be inserted in the flap of a collar from the back so as to extend substantially from top to bottom of the flap adjacent its edge, and means provided with both elements to detachably tie the same together; said members being bent out slightly from their lower ends, and the upper ends of the members have a similar bend but in the opposite direction.

2. A stay for soft collars comprising separate substantially straight stay elements adapted to be inserted in the flap of a collar from the back, bars extending toward each other from said elements intermediate their ends and having disengageable and cooperating fastenings on their adjacent ends, and means integral with the bars and elements and formed in part with the latter for connecting the bars to the elements; said elements being bent out slightly for a short distance at their lower ends and being similarly bent at their upper ends but in the opposite direction.

3. A stay for soft collars comprising separate stay elements, each element including a substantially straight wire member adapted to be inserted in the flap of a collar from the back so as to extend substantially from top to bottom of the flap, an arm connected to the member at its lower end and extending upwardly alongside the member to a point short of the upper end thereof, a downward U-bend on the upper end of the arm, and a bar projecting horizontally from the lower end of the bend; the bars of both elements having cooperating but disengageable fastening means on the outer ends of the bars.

4. A stay for soft collars comprising separate stay elements, each element including a relatively stiff member adapted to be insert-

ed in the flap of a collar from the back so as to extend substantially from top to bottom of the flap adjacent its edge, bars projecting horizontally from the members intermediate their ends and towards each other, cooperating and disengageable fastening means on the adjacent ends of the bars, and flat scrolls, disposed in planes parallel to the bars, formed on the upper end of the members.

5 10 In testimony whereof I affix my signature.
WILLIAM F. RAMONT.
